2 SHEETS—SHEET 2.

UNITED STATES PATENT OFFICE.

DANIEL L. HEALY, OF SAN FRANCISCO, CALIFORNIA.

PLOW.

1,359,371.

Specification of Letters Patent. Patented Nov. 16, 1920.

Application filed November 18, 1918. Serial No. 262,926.

To all whom it may concern:

Be it known that I, DANIEL L. HEALY, a citizen of the United States, residing at San Francisco, in the county of San Francisco, State of California, have invented a new and useful Plow, of which the following is a specification, in such full and clear terms as will enable those skilled in the art to construct and use the same.

10 This invention relates to a plow of the general type known as a gang plow and its particular plow is intended to be used in conjunction with a series of similar plows all operated together.

15 Other objects of the invention will appear as the description proceeds.

An embodiment of the invention is shown in the drawings in which the same reference numeral is applied to the same portion 20 throughout, but I am aware that there may be modifications thereof.

Figure 1 is a plan view of the complete plow with its steering frame,

Fig. 2 is a side elevation of the complete 25 plow and steering frame,

Fig. 3 is a side elevation of the furrow wheel and its segment guide,

Fig. 4 is a front elevation of the furrow 30 wheel segment guide showing the brace for attaching it to the frame of the steering gear,

Fig. 5 is a plan view of one of the axles of the plow,

Fig. 6 is a back elevation of the lever for 35 raising or lowering the line of pull upon the plow, and

Fig. 7 is a side elevation of one of the stub shafts used on the plow axle.

The plow steering gear comprises a draw 40 bar 1 which draw bar has suitable iron straps binding and stiffening it. These straps terminate in lugs 3 and 4 for the attachment to another draw bar but which forms no part of the present invention. The 45 draw bar 1 has a stiffening plate 5 across its top at the front of which is an eye bolt 6 to which the plow draft link 7 is connected. The draw bar has two other reinforcing plates 8 and 9 which plates have caster wheel 50 brackets 10 and 11 mounted on caster wheels 12 and 13 at the front of the machine.

At the rear of the plates 8 and 9 there are 55 depending brackets 14 and 15 in which are journaled wheels 16 and 17, so that the draw bar is supported by means of the wheels 12 13 and 16, 17. The draw bar is steered by

means of the two poles 18 and 19 which are connected to the forward portions of the caster wheel frames 10 and 11. In order to hold the draw bar mechanism in the proper position with respect to the furrow wheel 20 which is mounted on an arm 21 pivotally connected to the depending lugs 22 carried by the draw bar, there are two of the arms 21 united at their rear end in a 65 slide 23. This slide is freely movable in the segment guide 24.

This guide is carried by the bar 25 supported at its front end by the draw bar 1. The guide is braced by means of a diagonally 70 extending bar 26 which extends from the lower portions of the segment guide to the draw bar 1.

The plow drag link 7 passes through an elongated link 28 which is supported by a 75 lever 29 pivotally mounted on the post 30 on the back of the draw bar 1. A depending bracket 31 holds the link in the proper alinement; and said bracket is braced by means of a bar 32 which extends at an angle 80 therewith, and is connected with the draw bar 1 and which has openings in its upper end to provide for the lever 29.

The plow has two beams 33 and 34 which are joined together at their front ends, and 85 which stand at a distance from each other at their rear ends; each being connected to a plow standard as indicated at 35 and 36. These standards have mold boards 37 and 38 connected therewith respectively.

90 The drag link 7 is connected with the ring 39 at the front end of the plow beams which ring is adjustable as to height in the two depending brackets 40 and 41. These brackets have braces 42 and 43 connecting 95 them with the plow beams. The plow is supported when at work by the mold boards and by means of the two wheels 46 and 47. One of these wheels is carried by a stub axle 48 detachably connected with a transversely 100 extending axle 49 which axle 49 has a block 50 at one end for the connection of the stub axle thereto. The stub axle is threaded to receive a screw 52 on a block 53 which block holds it rigidly when mounted as shown in 105 Figs. 1 and 2. At the other end of the axle there is a rigid spindle 51 for the wheel 47, and this wheel may be held in place by the screw 52 and block 53 to which another plow axle may be connected.

110 The plow illustrated in this invention is intended to be used in connection with a

series of other plows and when so used, has flexible axles connected to the ends of the axles 49; but in the present instance, the blocks 53 are used to hold the wheels 46 and 47 in the desired rigid position.

The axle 49 has two drag links 56, 57 connected thereto, which links are connected with the lower end of a lever 58 pivotally mounted thereon on the frame of the plow and adjusted by means of the segment rack 59 and latch 60, whereby the length of the drag links is accommodated to different heights of the beams 33, 34 as will be presently explained. The axle 49 is rigidly connected with the lower end of two posts 61, 61' which posts are slideable through two plates 62 and 63 secured to the bottom and top respectively of the beams 33 and 34. At the upper end of the bar 61 there is a flat plate 65 which has a series of holes therein in order to enable the lever 66 to be connected therewith in different adjustments as may be necessary. The plows are lifted out of the ground by depressing the forward end of the lever 66, which is held in any given adjustment by means of the latch 67, engaging suitable notches in the rack bar 68; while the rear end of said lever is connected by means of a ring 69 and two links 70, 71, with the rear ends of the plow beams.

Since this particular plow is intended to be used in conjunction with an entire set of seeding apparatus, it has a rearwardly extending pole 72 to which the seeder is connected by means of a movable clevis 73. The first plow of the set has arms 74, 75 connected thereto which are in turn connected to a beam 76 for the purpose of pulling the harrow 77. Said harrow is connected to the plow beam 76 by means of two links 78, 79. This bar 76 is held in a fixed position with respect to the plows by means of rods 80, 81 and turn buckle 82, which rods are connected to a ring 83 at the rear end of the plate 8 on the main draw bar.

In operation the apparatus is connected to any suitable source of power traction engine, or a team, as may be desired, and is steered by means of the caster wheels 12 and 13, the furrow wheel 20 holding the plow steering mechanism in the desired track. As the apparatus is drawn forward, the

plows will turn over the furrow, the depth of the furrow being regulated by means of the lever 66; and as such regulations take place, the rods 56, 57 are kept tight by means of the lever 58.

The draw bar is made sufficiently wide to afford a walk for the plowman.

Having thus described my invention, what I claim as new and desire to secure by Letters Patent of the United States is as follows, express reservation being made of permissible modifications:

1. In a plow, the combination of a wheeled draw bar, a vertically movable pivoted arm connected with the draw bar, a furrow wheel carried by the arm, a plow frame connected with the draw bar carrying a plurality of mold boards and having a pair of supporting wheels vertically adjustable with respect to the frame of the plow.

2. In a plow, the combination of a draw bar, wheels for supporting said draw bar, a furrow wheel movable vertically for assisting in steering the draw bar, a plow frame connected with the draw bar, a plurality of mold boards carried by said plow frame, a pair of adjustable wheels for determining the depth of the furrow to be produced and for supporting the plows, and a pair of links for holding the plow wheels in a fixed position longitudinally with respect to the plow frame.

3. In a plow the combination of a draw bar, fixed wheels and caster wheels supporting said draw bar, a vertically movable furrow wheel to assist in tracking the draw bar, and a gang plow connected to the draw bar.

4. In a plow the combination of a draw bar, fixed wheels and caster wheels for supporting said draw bar, an arm pivoted to the draw bar at one end and freely movable vertically, a furrow wheel connected with said arm for guiding the draw bar, and a gang plow connected with the draw bar so placed as to cover the furrow in which the furrow wheel travels.

In testimony whereof I have hereunto set my hand this 8th day of November A. D. 1918.

DANIEL L. HEALY.
